UNITED STATES PATENT OFFICE.

JAMES F. ROCHE, OF BOSTON, MASSACHUSETTS, ASSIGNOR TO THE REGULAR ARMY AND NAVY UNION OF OHIO.

DESIGN FOR A BADGE.

SPECIFICATION forming part of Design No. 21,704, dated July 12, 1892.

Application filed April 21, 1892. Serial No. 430,129. Term of patent 3½ years.

To all whom it may concern:

Be it known that I, JAMES F. ROCHE, a citizen of the United States, residing at Boston, in the county of Suffolk, State of Massachusetts, have invented a new and original Design, 5 for a Badge, of which the following is a specification, reference being had to the accompanying drawing, forming part thereof.

The drawing represents my newly-designed 10 badge.

My design for a badge embodies, essentially, the representation on a rectangular body of an eagle with outstretched wings, together with the representation of an anchor arranged below the eagle. 15

I claim—

The design for a badge, substantially as herein shown and described.

In testimony whereof I have signed my name to this specification in the presence of 20 two subscribing witnesses.

JAMES F. ROCHE.
